UNITED STATES PATENT OFFICE.

JACOB P. HART, OF UPPER SANDUSKY, OHIO.

FODDER-HARVESTING MACHINE.

SPECIFICATION forming part of Letters Patent No. 425,609, dated April 15, 1890.

Application filed June 24, 1889. Serial No. 315,449. (No model.)

To all whom it may concern:

Be it known that I, JACOB P. HART, a citizen of the United States, residing at Upper Sandusky, in the county of Wyandot and State 5 of Ohio, have invented certain new and useful Improvements in Fodder-Harvesting Machines; and I do hereby declare the following to be a full, clear, and exact description of the invention, such as will enable others 10 skilled in the art to which it appertains to make and use the same.

My invention relates to improvements in the different parts necessary to construct a practical and efficient fodder-harvesting machine; and it consists of certain novel features 15 hereinafter fully described and claimed.

In following the description given reference will be necessary to the accompanying drawings, in which similar letters of reference 20 refer to corresponding parts in all the views.

Figure 1 is a perspective view of my improved fodder-harvester complete. Fig. 2 is a detail showing a section of the rear platform N, the gate, and the locking-rod Z, and brace X. Fig. 3 is a plan view of the bottom 25 of my harvester. Fig. 4 is a rear elevation.

Proceeding to describe the construction of my invention, I provide a front platform A, 30 on the under and rear edge of which I place an iron band H, which serves as the axle, the ends of which are bent upward on each side and serve as a means for attaching the adjustable axles upon which the carrying- 35 wheels are placed. Upon each side of such front platform I attach side bars B B, which are to be erected in a suitable position and extend to the rear end of the dropping platform N, and in connection with the rear gates 40 U U, which are hinged at the rear ends of side bars B B, and upright braces L L form the side frame-work of my harvester. The platform A is to be of a suitable width to enable the stationary knives D D on each side 45 to be in proper position to each receive a row of corn.

To properly receive and guide the stalks to the stationary knives D D, the same are placed at the rear of notches or mouths in 50 the platform, while the extending noses c c assist in this operation.

Midway between the center of the platform

and the sides thereof I erect upon each side the table O, consisting of the supports P P and laterals o o. The object of this table is 55 primarily to provide a means of support for the binding-rack T T. Such binding-rack T T may be of wood or metal, so formed that the rear ends shall be connected by a U-shaped loop, the ends of which point rear- 60 wardly and are notched on their inner side, as shown at t. The rack is further provided with the roller S, which may be provided on one end with suitable handle for turning same. To one end of this roller is attached 65 a cord or chain s', while the other end is provided with a small pin s. The object of this cord will be hereinafter referred to.

To assist the stationary knives D D in cutting the stalks, I provide upon each side revolving knives E E, which are suitably journaled in the projecting ends of platform A and operate from beneath by suitably-arranged bevel cog-wheels and pulley-wheels properly secured and held in position by 70 journal-boxes G and J J. The journal operating the revolving knives E E extends above the center of such knives sufficiently to form an attachment for the perpendicular shafts Q Q, to the upright ends of which are 75 secured the reels Y Y, having arms y y, as shown. Immediately in the rear of the reels Y Y, I attach to the upper side bar B the inwardly-reaching springs b b.

In order to form a continuation of the front 85 platform A, I pivotally attach to the lower side bars B the dropping platform N. To the middle of the upper side of the dropping platform N, I attach longitudinally its entire length operating-lever K, the front end of 90 which is continued so as to reach to the front edge of platform A, and is there secured in position in stays a a by a suitably-arranged pin. Midway between the operating-lever K and the sides of platform N, I place longitudinal ribs n n, which reach the entire length of such platform. The gates U U, being secured at their outer ends to side bars B B, are secured in the center by means of suitably-provided eyes V V, in which is to be 100 placed the locking-rod Z when it is desired to secure the gates.

In order to additionally brace the upper side of the gates, I provide an inward-reach-

ing brace X, the front end of which is secured to the upper side of the front end of operating-lever K, while its rear end is provided with an eye and is attached to the gates 5 by locking-rod Z. The perpendicular shafts Q Q are suitably journaled to the inner sides of the side bars B B. Reaching transversely across the middle of dropping platform N, I arrange the sliding bar W, provided on 10 its under side with notches w w to coincide with the longitudinal ribs and operating-lever K. On each end of sliding bar W ropes or other suitable appliances are attached, the front ends being provided with hooks to engage with each other, while the rear ends are provided with rings, the object of which will 15 hereinafter be referred to.

Proceeding now to describe the operation of my invention, the machine is designed to 20 be operated with one horse as a motive power, and two men upon the machine within the table receive the corn as it comes from the reels. The machine is constructed so as to cut two rows of corn each time it is drawn 25 through the field, the horse traveling between the rows. The revolving knives E E revolve immediately above the stationary knives D D, severing the stalks as they are guided to such knives by means of the forward-reaching noses c c and the rounded ends of the 30 platform A, while the reels Y Y place the severed stalks in position upon the inward-reaching springs b b, where they may be secured by the men provided for the purpose and placed in an upright position against the gates U U and upon the rear platform N. When a sufficient number of stalks has been 35 gathered, the rope attached to roller S at pin s' is placed within the groove t and then 40 brought entirely around the stalks of fodder upon the rear platform and the free end of same attached to the pin s on the other end of roller S. The handle on the end of roller S is then turned, causing the slack end of the 45 rope to be taken up and the fodder bunched tightly in a "shock," when it may be secured by twine or other suitable material. The roller S may then be reversed, releasing the 50 rope around the shock, when the binding-rack T T may be elevated. The pin in the stays may then be withdrawn, releasing the front of lever K, while the locking-rod Z is removed from the eyes V V of the gates, enabling such gates to be opened and further 55 causing the rear of platform N to drop to the

ground. The forward ends of the rope in sliding bar W are hooked together around the base of the front side of the shock, while the rear ends of such rope having the rings are to be secured to the earth by a pin or 60 other suitable means, when the machine may be started, and by such action the shock is withdrawn from the platform N. The forward end of operating-lever K is then again secured in stays a a, the gates are again closed, 65 and binding-rack T T is thrown back into position, and the machine is ready to repeat the operation. The gates U U are provided on their inner sides with projecting eyelets arranged to receive the locking-rod Z, which 70 passes through such eyelet, thereby securing the gates when closed. The bar X extends from the front end of the lever K back to the top of rod Z, by which it is secured in such position by said rod passing through a hole 75 provided in the end of said brace.

Having described my invention, what I claim as new, and desire to secure by Letters Patent, is—

1. The combination, with a fodder-harvesting machine having revolving and stationary knives, of the dropping platform N, hinged to the stationary platform A and provided with the forward-reaching lever K and longitudinal ribs n n and the sliding bar W, having 80 ropes attached to the end thereof, as set forth.

2. The combination, with a fodder-harvesting machine having stationary and revolving knives, of the inward-reaching gates U U, 90 hinged to the rear ends of side bars B B and secured at their inner ends by locking-rod Z and brace X, as shown.

3. The combination, with a fodder-harvesting machine having revolving and stationary knives, of the sliding-bar W, provided on its under side with notches w to coincide with the longitudinal ribs n n and lever K, the inward-reaching springs b b, reaching inwardly from the side bars B B, and the binding-rack T T, provided with roller S and attached to table O, all substantially as described, and for the purpose named.

In testimony whereof I affix my signature in presence of two witnesses.

JACOB P. HART.
